(57) **CLAIM**

The ornamental design for a weight lifting bar collar, substantially as shown and described.

DESCRIPTION

FIG. 1 is a front perspective view of a weight lifting bar collar showing our new design;

FIG. 2 is a bottom perspective view thereof;

FIG. 3 is a front elevational view thereof;

FIG. 4 is a rear elevational view thereof;

FIG. 5 is a right elevational view thereof;

FIG. 6 is a left view thereof;

FIG. 7 is a top view thereof; and,

FIG. 8 is a bottom view thereof.

The broken line showing of portions of the weight lifting bar collar form no part of the claim.
